(57) **CLAIM**

The ornamental design for a closure, as shown and described.

DESCRIPTION

FIG. 1 is a front perspective view of a closure according to the new design;

FIG. 2 is a rear perspective view thereof;

FIG. 3 is a front elevated view thereof;

FIG. 4 is a rear elevated view thereof;

FIG. 5 is a side view thereof;

FIG. 6 is a top view thereof; and,

FIG. 7 is a bottom view thereof.

The broken lines in the drawing depict environmental subject matter only and form no part of the claimed design.
